UNITED STATES PATENT OFFICE.

RAY SOSEMAN, OF BLOOMFIELD, IOWA.

SPADER ROLLER.

Application filed March 10, 1928. Serial No. 260,604.

The object of my invention is to provide a spader roller of simple, durable, and comparatively inexpensive construction.

A further object of my invention is to provide a spader roller of the type herein disclosed in which a plurality of roller disks are rotatably mounted on a shaft whereby they are independently rotatable on the shaft for preventing them from collecting mud and to allow easy turning of the roller around corners, these roller disks being provided with diagonal projections on their peripheries.

Still a further object is to provide in connection with the roller a suitable frame work for pulling the roller across ground which has been plowed for the purpose of pulverizing the clods and getting the ground into better shape for planting.

Still a further object is to provide a second roller in connection with the roller already mentioned with the diagonal projections on the second roller slanting in a direction opposite those on the other one for the purpose of forming depressions in the ground over which the device travels which are broken up into crosses to prevent the formation of small ditches down which rain might wash the soil away.

Still a further object is to provide half the disks on one shaft with the projections in a direction opposite to those on the other half so that the device will not have a tendency to run toward one side but will maintain a straight course behind the tractor or team being used as motive power for the device.

With these and other objects in view my invention consists in the construction, arrangement and combination of the various parts of my device, whereby the objects contemplated are attained, as hereinafter more fully set forth, pointed out in my claims and illustrated in the accompanying drawings. Although the invention is susceptible of a variety of embodiments, it is unnecessary to fully describe and illustrate more than one in order to give a full understanding of the invention both from its structural and functional standpoints. Accordingly, I have illustrated a preferred and desirable embodiment of the invention in the accompanying drawings in which:

Figure 1 is a plan view of a land roller embodying my invention and illustrating the two rollers journaled on a suitable frame work.

Figure 2 is a side elevation of the same.

Figure 3 is a perspective view of one of the roller disks a plurality of which are used to form the roller.

Figure 4 is an enlarged sectional view on the line 4-4 of Figure 2; and

Figure 5 is a sectional view on the line 5-5 of Figure 4 illustrating one of the disks secured to the shaft on which it is mounted.

On the accompanying drawings I have used the reference character A to indicate generally one of the rollers. The other roller is indicated by the reference character B. The rollers A and B are mounted on shafts 10 and 12 the ends of which are journaled in bearings 14 and 16.

A frame work C is provided to which the bearings 14 and 16 are secured. The frame C comprises two symmetrically similar members 18 and 20 which terminate in forwardly projecting arms 22 spaced from each other. A pivot plate 24 is pivoted by means of the bolt 26 to the arms 22. A tongue or draw bar 28 is secured to the pivoted plate 24. The frame work C and the draw bar 28 merely illustrate one embodiment of a suitable frame work for my device and it is obvious that a frame work of any suitable character to suit the conditions encountered may be provided to be substituted for the frame C. For instance in a horse drawn device it would be desirable to have supporting means for a seat for the driver.

The rollers A and B comprise a series of disks 30 and 32. Each of these disks consists of a rim 34 having projections 36 extending therefrom. Each disk also has a hub 38 to fit over the respective shafts 10 and 12 whereby the disks may freely rotate thereon. The projections 36 on the disks 30 slant in one direction and those on the disks 32 slant in an opposite direction.

It will be noted that half of each roller A and B is provided with disks 32 for the purpose of preventing a tendency of the device to run sideways when being drawn across the ground.

It will be further noted that disks 30 are used on the roller B directly behind the disks 32 on the roller A. This results in a row of depressions 42 (see Figure 1), being formed by the roller disk 32 as shown in dotted lines and depressions 44 being formed over the depressions 42 by the roller disk 30. This prevents the formation of ditches and obviates the result of small water ways being formed so that when it rains the soil will be washed away.

The ground over which the roller travels is pulverized and broken up into a series of crosses which prevent any tendency of ditches being formed.

5 As a further advantage in preventing the formation of ditches the projections on adjacent disks 30 and 32 will usually be staggered relative to each other so that staggered depressions are formed in the ground as the 10 roller travels across it instead of continuous depressions which would have a tendency to form ditches. From the foregoing description the advantages of my device will be readily apparent.

15 Some changes may be made in the construction and arrangement of the various parts of my invention, without departing from the real spirit and purpose of my invention, and it is my intention to cover by my claims any 20 modified forms of structure or use of mechanical equivalents, which may be reasonably included within their scope.

I claim as my invention:

1. A spader roller of the class described comprising a frame, a shaft thereon, a plurality of roller disks rotatable on said shaft, diagonal projections on the periphery of each disk, a second shaft behind the first one, a plurality of disks rotatable on said second shaft,

30 diagonal projections on said second mentioned disks inclined in a direction opposite to the ones on the disks on the first mentioned shaft.

35 2. A spader roller of the class described, comprising a frame, a shaft thereon, a plurality of roller disks rotatable on said shaft, diagonal projections on the periphery of each disk, a second shaft behind the first one, a plurality of disks rotatable on said second shaft, diagonal projections on said second 40 mentioned disks inclined in a direction opposite to the ones on the disks on the first mentioned shaft, the projections on adjacent disks being free to assume staggered relation with respect to each other.

45 3. A spader roller of the class described comprising a frame, a shaft thereon, a plurality of roller disks rotatable on said shaft, diagonal projections on the periphery of each disk, a second shaft behind the first one, a plurality of disks rotatable on said second shaft, diagonal projections on said second 50 mentioned disks inclined in a direction opposite to the ones on the disks on the first mentioned shaft, the projections on half the disks 55 being of opposite inclination.

Des Moines, Iowa, February 4, 1928.

RAY SOSEMAN.
